UNITED STATES PATENT OFFICE.

EDWARD J. SNELL, OF CORNING, NEW YORK.

GARMENT-HANGER.

1,113,061.

Specification of Letters Patent.

Patented Oct. 6, 1914.

Application filed January 10, 1913. Serial No. 741,273.

To all whom it may concern:

Be it known that I, EDWARD J. SNELL, a citizen of the United States, residing at Corning, in the county of Steuben and State of New York, have invented new and useful Improvements in Garment-Hangers, of which the following is a specification.

This invention relates to a garment hanger, the main object thereof being to provide a combination device upon which a coat and trousers may both be hung, and which may be folded into a very small and compact form so as to accommodate the same to the length of any receptacle in which it may be placed and to economize space therein.

A further object is to provide a device of this character which is constructed almost entirely of metallic wire which is bent into the desired shape so as to form a neat appearing and simply constructed device which will be efficient in operation, durable and inexpensive in the cost of manufacture.

The invention consists in the features of construction, combination and arrangement of parts, hereinafter fully described and claimed, reference being had to the accompanying drawing in which:

Figure 1 is a perspective view of the device in open, operative position; Fig. 2 is a front elevation of the same in collapsed, inoperative position; and, Fig. 3 is a longitudinal sectional view through the device as shown in Fig. 1.

In the drawing, the numerals 1 and 2 designate the supporting arms of the device which are pivotally connected at their inner ends in the manner which will be presently described, and which are adapted either to be extended into operative position, as shown in Fig. 1, or to be folded into inoperative position, as shown in Fig. 2.

Each supporting arm is constructed from a single piece of metallic wire and is bent in a substantially U-shape to provide the side portions 3 and 4, which latter are preferably converged toward each other. The side portion 4 of the arm has its end bent to form a loop 5 embracing a pivot member 6 adjacent one end thereof, the member 6 being constructed of a single piece of wire, or being in the form of a double wire, as shown, it being necessary to provide enlargements upon the ends thereof. In constructing the member 6, in the manner shown, these enlargements are in the form of a loop 7 at one end and the outbent extremities 8 at the

other end, the enlargements thus formed serving to retain the position of the pivotal parts of the device upon the pivot member. The opposite side portion 3 of each arm is bent into the form of a loop 9 embracing the pivot member in juxtaposition to the loop 5 on the side portion 4 of the other arm. Each side portion 3 is initially cut longer than the side portion 4 in order that its extremity will extend past the loop 9 thereon to provide a stop member 10, whose lateral extension 11 is adapted to engage beneath the side portion 4 of the other arm when both arms are in extended position with respect to each other. The arms 1 and 2 are curved downwardly so that the hanger as a whole will be bowed to properly fit the shape of the shoulders of a coat or similar garment.

A supporting guide member 12 has its outer end secured fixedly to the end loop 13 of each foldable arm by means of a loop 14, or in like manner, and has its inner end pivotally attached by means of the loop 15 to the pivot member 6 between the pivoting loops of the side portions of both arms. Each guide member 12 includes an outer portion 16, which is substantially horizontal when the device is not used, and an upwardly inclined inner portion 17, thus affording structure which will tend materially to reinforce the corresponding arm of the device. A longitudinally movable trouser clip 18 is slidably mounted upon the outer portion 16 of each member 12, which affords a support for the clip and serves likewise as means for guiding the same during its movement into different adjusted positions. These spring clips 18 may be adjusted relatively when the device is in operative position with its arms extended, in order that trouser ends of different widths may be supported by the same, or these clips may be used to hang a skirt or any other garment as desired.

A supporting hook 19 for the device has its lower end formed into a loop 20 which embraces the pivot member 6 between the loops 15 provided upon the guide members 12, a sufficient space being provided therebetween for the reception of the hook loop.

The clips 18 may be used to grip one of the side portions of the opposite arms of the device when the device is in folded position, in order that it may be effectively retained in this position.

From the foregoing description, taken

in connection with the accompanying drawing, it will be apparent that I have provided a simply constructed and efficient garment hanger which may be put to a variety of uses, and which will be very inexpensive to manufacture, due particularly to the fact that it is formed throughout by the bending and twisting of the pieces of wire which form its essential component parts, no soldering or like expedient of construction being resorted to.

What is claimed is;

A garment hanger comprising a pivot member, a pair of folding arms in the form of substantially U-shaped loops of wire having their ends pivotally connected to the said pivot member adjacent to the ends thereof, the outermost curved portions of said arms being bent downwardly, a supporting hook attached medially to the pivot member, means for limiting the movement of said

arms into extended position, a reinforcing guide member for each arm having its outer end connected with the outer curved portion of the arm medially thereof and its inner end portion inclined upwardly toward the pivot member, the inner ends of the said guide members being connected with the pivot member on opposite sides of the supporting hook, the outer end portions of the said guide members being arranged in substantial alinement with each other when the arms are extended, and an attaching device 35 slidably mounted upon the outer portion of each guide member.

In testimony whereof I affix my signature in presence of two witnesses.

EDWARD J. SNELL.
